UNITED STATES PATENT OFFICE.

JOHN ZILLIOX, OF ORCHARD PARK, NEW YORK.

WRENCH.

Application filed August 26, 1924. Serial No. 734,310.

This invention relates to a wrench of the type which is more generally known as a machine wrench, and which is adapted to grasp or embrace the heads and nuts of bolts or similar objects with the purpose of turning the same or holding the same against turning in the usual or well-known manner.

It is the object of this invention to provide a wrench of this character having a head which is removable from the handle bar so as to permit heads having different sizes of sockets or jaws to be applied to the same handle bar, more particularly to a locking device whereby such heads of the handle bar are coupled or held together so that they cannot become accidentally separated while the wrench is being used.

In the accompanying drawings;—

Fig. 1 is a side elevation of a wrench embodying my improvements,

Fig. 2 is a similar view of part of the handle bar and the wrench broken away,

Figs. 3 and 4 are side elevations of the head and handle bar of the wrench detached from each other,

Fig. 5 is a cross-section taken on line 5—5 of Figure 3, and

Figs. 6 and 7 are edge views of the head and handle bar of the wrench detached from each other.

Similar characters of reference indicate like parts in the several figures.

The numeral 10 represents the head of the wrench and 11 the handle bar of the same which is detachably connected with the head for the purpose of permitting heads having different sizes of sockets or differently spaced jaws to be mounted on the handle.

This head in the form shown in the drawings is constructed of a substantially flat piece of metal and is provided at its front end with two jaws 12, 13, which are arranged at an angle relative to the length of the head so that the socket or recess 14 between these jaws can be applied either in one position or in a reverse position to the object which is to be engaged by the wrench head, such for instance, as the head and nut of a bolt and thus enable the latter to be held or turned as best suits the particular circumstances or conditions under which the wrench is being used.

On opposite sides of its rear end the wrench head is provided with two side recesses 15 which extend forwardly from the

rear end of the head and each of which is provided with upper and lower longitudinal walls 16 and 16 which are parallel and a rounded front wall 17 which forms the inner end of this recess. Between the recesses 15, 15 is arranged a narrow web or rib 18 which extends to the rear end of the wrench head.

On its front end the handle bar is provided with a vertical slot 22 extending rearwardly from the front end of the same and transversely from one side edge to the other so as to form two arms 23, 23 on opposite sides of this slot. These arms are adapted to straddle the web 18 and to enter the recesses 15, 15, on opposite sides of the same. The longitudinal edges 24, 24 of each of the arms 23 are parallel and the distance between the same is equal to the distance between the parallel longitudinal sides 16, 16 of the respective recesses on the head, and the front end 25 of each arm corresponds in curvature to the curvature of the inner end 17 of the respective recess of the head so that when these parts engage with each other they form a snug fit, as shown in Figure 1, whereby the head and handle bar are caused to turn in unison when using the wrench and avoid any looseness or rattling between these parts which otherwise would occur if there was any slack in the joint between the same. A wrench of this character is shown in my co-pending application for patent Serial Number 523,982, filed December 21, 1921, and patented on Apr. 28, 1925, Number 1,535,281.

It has been found in practice that when the head and the handle bar are only connected by a frictional contact with each other that the handle, in some instances, is liable to become detached from the head, especially when the jaws of the head engage with unusually tight fit upon the object which is being engaged and also when reaching into places which are difficult of access and when lowering the wrench head by means of the handle bar into a position where the head is liable to drop off from the handle bar by gravity if the frictional engagement between the same is not very good.

The present invention is, therefore, intended to permit of positively locking the head and handle bar together, but permitting the same to be separated at will when this is desired, and thereby positively preventing separation of the head and handle bar under

all circumstances and wholly regardless of whether the frictional fit between these parts is sufficient to maintain them in operative relation. In the preferred form of 5 this locking device, as shown in the drawings, the same is constructed as follows;

These locking means on the web in the present instance, consist of a notch 19 extending forwardly from the rear edge of 10 the web and provided on its upper and lower sides with undercuts 20 forming forwardly facing shoulders 21 on opposite sides of this notch. The shoulders are preferably inclined so that these two shoulders converge forwardly and in effect form two hooks.

Mounted on the handle bar within the rear end of the slot 22 is a latch which in 20 its preferred form consists of a forwardly projecting hook 26, a finger piece 27 projecting laterally from the rear end of the hook and extending beyond one edge of the handle bar, and a retaining or stop finger or guide lug 28 projecting laterally from 25 the opposite side of the rear end of the hook but terminating within the border line of the handle bar, thereby forming in effect a substantial T-shaped catch or latch. This latch is pivotally mounted on the handle bar 30 by means of a pivot pin 29 passing transversely through the arms of the handle bar and through the latch at the junction between this hook, finger piece and retaining finger. This latch is yieldingly held in a 35 position in which the beak 32 of its hook is maintained in line with one or the other of the shoulders 21, 21 of the wrench head, this being preferably accomplished by means of a wire spring having a shank 30 interposed 40 between the rear side of the latch and the bottom of the slot 22 and having a pin 31 at one end which engages with a corresponding opening in the finger piece 27 while its opposite end engages with the rear 45 end of the slot 22 at a point relatively to the pivot pin 29 which is opposite to the finger piece 27.

When pushing the jaws of the handle bar into the recesses of the wrench head the beak 50 of the latch hook springs over one of the shoulders 21 of the wrench head and interlocks therewith so as to prevent separation of the head and the handle bar by lengthwise movement of these parts away from 55 each other. When it is desired to separate these parts the latch may be moved into its unlocked position by pressing forwardly on the finger piece 27, thereby disengaging the beak 32 of the hook from the respective shoulder on the wrench head and permitting withdrawal of the handle bar and wrench head from each other. Upon now reversing 60 the wrench head and handle bar one relatively to the other the hook 26 of the latch 65 may be engaged with the other shoulder 21

of the wrench head upon re-assembling the head and the handle bar, whereby the same are interlocked in substantially the same manner in which this occurred in the previous instance. By this means the head may 70 be attached to the handle bar with its socket 14 inclined either in one direction or the other, relatively to the longitudinal axis of the wrench and thus permits of using the wrench in the manner most convenient for 75 turning or holding any particular object. The inner side of the beak 32 of the locking hook 26 is inclined like the inclination of the shoulders 21, 21 so that a longitudinal pull of the head and handle bar relatively to 80 each other, will not permit of uncoupling the same, but instead, will cause the locking device to grip more firmly.

If desired, the socket 14 of the wrench head may be formed centrally and symmetrically thereon in the manner in which some machine wrenches are now made. Also, if desired, the notch 19 may be provided with a shoulder 21 on only one of its sides. For convenience, however, of re-assembling the 90 wrench head and handle bar and interlocking the same in reverse positions it is desirable to provide the notch 19 with locking shoulders 21 on both of its sides, inasmuch as this will avoid the necessity of exercising 95 any particular care when slipping the handle on to the head because in either case the latch will interlock properly with the web and the wrench head.

The retaining finger or guide lug 28 on 100 the latch provides a wide bearing surface for the latch on the handle bar which operates to prevent the latch from tilting and binding on the pivot pin 29 and also ensures greater durability of these parts and it also 105 forms a stop by engaging the spring 30 for limiting the releasing movement of the catch.

This means of locking the head on the handle bar is very simple in construction and 110 can be produced at low cost. The same is installed in such a manner that the same does not weaken the wrench or render the same liable to get out of order, and it can be very 115 easily manipulated by the thumb of the hand while the wrench is in use, thereby enabling objects to be held or turned conveniently and with facility.

I claim as my invention:—

A wrench comprising a head provided on 120 its front end with a socket adapted to receive the article to be engaged and provided on opposite sides of its rear end with recesses which are separated by an intervening web, a handle bar provided with a 125 longitudinal slot extending from its front end rearwardly and forming two arms, said slot being adapted to receive said web and said recesses being adapted to receive said arms, the rear end of said web being pro- 130

vided with a notch which is undercut on its opposite sides forming two forwardly facing shoulders, a T-shaped latch arranged within said slot and pivoted to said handle and having a hook projecting longitudinally forward from said pivot and adapted to engage with either of said shoulders and a cross-bar having its ends projecting laterally in opposite directions from said pivot, 5 one end of said cross-bar forming a finger-piece and having a slit in its rear side, and the other end of said cross-bar forming a stop which is adapted to engage with the rear end of the slot in said handle bar, and an L-shaped spring arranged between the rear side of said catch and the handle bar and having one end engaging said slit and the other end engaging the back of the slot in the handle bar. 15

JOHN ZILLIOX.
